UNITED STATES PATENT OFFICE.

CARRICK PAUL, OF HURSTVILLE, NEW SOUTH WALES, ASSIGNOR TO THE PACIFIC PEARL FISHING COMPANY, LIMITED, OF SYDNEY, NEW SOUTH WALES.

DIVING APPARATUS.

SPECIFICATION forming part of Letters Patent No. 581,174, dated April 20, 1897.

Application filed October 13, 1896. Serial No. 608,777. (No model.) Patented in New South Wales July 16, 1896, No. 6,729, and in Queensland August 7, 1896, No. 3,482.

To all whom it may concern:

Be it known that I, CARRICK PAUL, civil engineer, a subject of the Queen of Great Britain, residing at Carrington Avenue, Hurstville, near Sydney, in the British Colony of New South Wales, have invented new and useful Improvements in Diving Apparatus specially applicable for Pearl-Fishing, (for which an application for Letters Patent was filed in 10 the British Colony of New South Wales July 16, 1896, No. 6,729, and in the British Colony of Queensland August 7, 1896, No. 3,482,) of which the following is a specification.

This invention relates to diving apparatus 15 specially devised for undertaking submarine work of the deepest character, and specially pearl-fishing, and is practically safe and easy in operation.

The diving apparatus to which these improvements specially refer consists of those kinds in which the workers or operators are enclosed in a shell or casement which is in communication with the atmosphere above the level of the water-surface, and these improvements have been specially devised in order 25 that the workers or operators may have control over the sinking and rising of the shell or casement, and they have been devised, secondly, in order that the operator may have 30 tools or grippers easily manageable.

These improvements in diving apparatus specially applicable for pearl-fishing consist of the combination and arrangement, with a shell or casement for containing the operators, of a second and telescopic shell or casement adapted to be closed in upon the first-mentioned casing to lessen the displacement of the whole apparatus, so that said apparatus will sink, and adapted to be extended telescopically from off the first-mentioned shell or casement, so as to increase the displacement of the apparatus, so that such apparatus will rise through the water to the surface. The joint between the inner and outer shell 45 or casement is of course practically air-tight and waterproof, and the second or outer shell or casement is in communication with the source of air-supply to the apparatus, so that the said air-supply will assist the telescopic

outward movement of the second shell or casement. 50

These improvements further consist of the special combinations and arrangements of various parts hereinafter described and claimed.

In order that this invention may be clearly 55 understood, reference will now be made to the drawings herewith, in which—

Figure 1 is a longitudinal sectional elevation of an improved diving apparatus specially applicable for pearl-fishing constructed according to these present improvements with the second and outer telescopic shell or casement in its closed-in position, making the apparatus of less displacement and in its sinking arrangement, and also showing in dotted lines 65 the second or outer telescopic shell or casement in its extended position, giving the apparatus its greatest displacement and converting it into its rising arrangement. Fig. 2 is a back end view. Fig. 3 is a cross-section on line *a a*, Fig. 1; and Fig. 4 is a front end view, respectively, of the same apparatus. 70

A is the main shell or casement, having extending upwardly a dome or chest *A'*. On this dome or chest *A'* is a door or cover *A*², 75 adapted to make an air-tight joint thereon. Outwardly of this casement *A* and air-tightly attached, so as to slide telescopically thereon, is a second shell or casement *B*. Through the door or cover *A*² pass telescopic pipes *C* and *D*, 80 the former, *C*, being connected with the air-pump on shore or pump or vessel above the surface of the water for supplying the necessary fresh air to the shell or casement *A* for the use of the operators, said supply being received into said casement *A* through cock or tap *C'*, the amount of opening of which may be regulated to the desire of the operators. Said pipe *C* is connected to a three-way cock or valve *C*² on the back end of the shell or 85 casement *A*, said three-way cock having an entrance into the casement *B* and into the casement *A*, as well as its connection to pipe *C*. Said cock *C*² may be regulated so that the full supply of air (apart from that passing 90 through cock *C'*) may be turned into casement *B* and thus tend to extend it telescopically, or connection may be made, through said cock 95

C^2 , between the air in shells A and B, so as to enable the shell B to be indrawn over the casement A. The pipe D is carried to the surface and provides an escape for the vitiated 5 or surplus air in the casement A and at the same time forms a protector for the pipe C. In the casement A are gages E and E', the former, E, for indicating the pressure of the water upon the apparatus and the latter, E', for indicating the pressure of air within the 10 shell B.

In the shell A is a dead-weight F, adapted to slide upon a rod F', held by stanchions or pillars F². Said weight F is adapted to be 15 easily shifted backward and forward, as may be required, by means of endless wire or rope F³, running around pulleys F⁴ on the end of the stanchions. Affixed to the end of the shell B and passing through female screw or nut 20 G', affixed to the shell A, is a screw-shaft G, and passing through both the shells or casements A and B and through respective stuffing-boxes H² and H³ thereon is a shaft or spindle H, on the outer end of which is a screw 25 or propeller H'. The inner ends of the screw G and propeller shaft or spindle H pass through and have bearings in a diagonal stay J. The outer end of this diagonal stay J has soles J', which work in guides J² upon the 30 shell A, and this diagonal stay J forms a steady-piece and guide in the relative movements of the shells or casements A and B. The inner ends of both the screw G and the shaft or spindle H have square ends, on 35 which will take a crank-handle, so that the requisite motion to propel the apparatus through the water backward and forward may be given to the propeller H' and so that the necessary motion to extend or to indraw the 40 shell or casement B over the shell or casement A may be given to the screw G. An air-tight and waterproof door B' is provided in back end of the shell or casement A, so that, if desired, a communication may be made between 45 the interior of the respective casements A and B and so that the gland H³ and the bearing G³ may be lubricated and attended to as required.

Where necessary in the shell or casement 50 A, and particularly in the front end, are ports or light-holes, those illustrated being marked K, one above and one below the gripping or lifting appliances.

The lifting and operating appliances consist of an outer pipe or casting L, and it has a ball L' seated exteriorly on the end of the nozzle-piece L² and retained in such position by means of the pressure of the water upon 55 an india-rubber envelop L³ pressing upon said casing L and prevented from actual contact therewith by conical spring L⁴, but forming a practically air-tight and waterproof joint around said casing or pipe L. In the 60 ends, both inner and outer, of said casing L are stuffing-boxes or glands L⁵, taking around a pipe or outer handle M', surrounding rod-

handle M. The outer end of said pipe-handle M' terminates in a female thread or nut M², through which passes the screwed end of the rod M. The inner end of said outer handle 70 M' terminates in stuffing-box or gland or other air-tight joint M³ and the operating-handle M⁴, while the rod M terminates in an operating-handle M⁵. On the outer end of the female thread or nut M² are jointed the claws 75 N, which may be of any desired shape and capacity. Passing through slots in said claws N are the ends M⁶ of T-piece on the outer end of rod or handle M. Now by the manipulation of the two handles M⁴ and M⁵ and the 80 flexibility of the india-rubber cone L³ and spring L⁴ the claws N may be operated to pick up anything within reach of their length. Said claws N are drawn together and parted from one another by the revolution of the 85 rod M in the female screw or nut M², as is easily understood, extending or indrawing the end M⁶ of the rod M between the said claws N.

In operation the workers enter the casement A through door A², which is then tightly 90 fastened on top of dome or chest A'. Then to sink the apparatus they open connection by three-way cock C² between the casements A and B and then revolve screw G, so that the casement B will telescopically close upon 95 casement A and reduce the displacement of the apparatus. When the weight overcomes the displacement, the apparatus sinks. When on the bottom or upon any wreckage or submarine workings, the operator regulates the 100 "set" or inclination of the apparatus by manipulating the endless cord F³, so as to place the dead-weight F in such position as required. To regulate the quantity and pressure of the air-supply in the casement, 105 the cock C' is handled to requirements. To pick up pearl-shell or other objects, the handles M⁴ and M⁵ are operated as before described and the products or holdings of the claws N are released over a basket or receptacle (not shown) which depends from the 110 overhead or above water working station. To move the apparatus backward or forward, the spindle H is revolved by crank-handle and the propeller H' causes the desired alteration of position. To rise to the surface, the 115 cock C² makes connection of air-supply pipe C with interior of casement B and the screw G is revolved to extend the shell or casement B, and when the displacement becomes in excess of the weight the apparatus rises to the 120 surface when the workers are released through door or cover A².

Having now particularly described and ascertained the nature of my said invention and in what manner the same is to be performed, I declare that what I claim is—

1. In diving apparatus of the class set forth the combination with a shell or casement containing the operators, of a second and telescopic outer shell or casement adapted to air-tightly slide upon said first shell or casement 130

so as to reduce, or increase as the case may be, the displacement of the apparatus, substantially as herein described and explained.

2. In diving apparatus of the class set forth 5 the combination with a shell or casement containing the operators, and having ports or lights therein, of a ball-jointed casing for rods or handles, of claws or gripper sitting upon a nozzle-piece and held in place by a flexible cone, substantially as herein described and explained.

3. In diving apparatus of the class set forth, 10 the combination of the telescopic shells or

casements A B, the threaded shaft G passing through a nut G' fixed in one end of the shell 15 A and journaled in a bearing fixed in the end of the shell B, a spindle H journaled in bearings in the ends of said shells and in a diagonal stay J, and guides J² in which said diagonal stay is movably seated, substantially as 20 shown and described.

Dated this 8th day of September, 1896.
CARRICK PAUL.
